Primary Examiner — John Windmuller

Assistant Examiner — John R Yeh

(57) **CLAIM**

The ornamental design for a snow removal tool, as shown and described.

DESCRIPTION

FIG. 1 is a front view of a snow removal tool showing my new design;

FIG. 2 is a rear view of the snow removal tool;

FIG. 3 is a left side view of the snow removal tool;

FIG. 4 is a right side view of the snow removal tool;

FIG. 5 is a top view of the snow removal tool, a bottom view being a mirror image thereof; and,

FIG. 6 is a top front side perspective view of the snow removal tool.
